UNITED STATES PATENT OFFICE.

JOSEPH RENÉ AYOTTE, OF CHICAGO, ILLINOIS.

SPARK-PLUG.

1,287,822.

Specification of Letters Patent.

Patented Dec. 17, 1918.

Application filed September 17, 1917. Serial No. 191,682.

To all whom it may concern:

Be it known that I, JOSEPH RENÉ AYOTTE, a subject of the King of Great Britain, residing at Chicago, in the county of Cook 5 and State of Illinois, have invented certain new and useful Improvements in Spark-Plugs, of which the following is a specification.

My invention relates to improvements in 10 spark-plugs for internal combustion engines and more particularly to what is commonly termed a spark-gap for association with the outer end of the plug.

One of the objects of my invention is to 15 provide a spark-gap which can be readily secured on the outer end of a spark-plug thereby becoming a permanent part of the plug to which the terminal of the high-tension cable may be readily connected.

20 Another object of my invention is to provide a spark-plug with a spark-gap incorporated in the outer end thereof with the terminal of the spark gap positioned in practically the same location as the terminal 25 of an ordinary spark-plug would be positioned.

A further object of the invention is to provide a spark-gap which may be readily attached or detached from the outer end of 30 the insulating core of a spark plug, having windows formed in the side wall thereof through which the operation of the gap may be readily observed.

A still further object of the invention is 35 to provide a rugged, sturdy device which may be manufactured at low cost and will withstand the punishment and abuse to which automobile accessories of this character are subjected.

40 Still other and further objects will become readily apparent to those skilled in the art from a consideration of the following description and drawings wherein:

Figure 1 is a side-elevation of my improved spark plug.

Fig. 2 is a longitudinal sectional view therethrough.

Fig. 3 is a transverse, horizontal sectional view on the line 3—3 of Fig. 1.

50 Fig. 4 is an end view of the spark plug.

Fig. 5 is a side elevation of the insulating core detached from the other parts of the plug, and,

Fig. 6 is a perspective view of the terminal electrode detached from the spark gap.

Spark gaps are now a commercially well known article for use in association with the spark plugs of internal combustion engines and it is unnecessary therefore to discuss the theory of operation or the advantages incident 60 to their use. My invention lies principally in the structural arrangement of the spark gap together with its means for attachment to the outer end of the insulating core of a spark plug. 65

In general the apparatus comprises a hood, or casing clamped over the outer end of the spark plug core and carrying in its center a separable member which extends through the top of the hood to provide at its 70 inner end an electrode spaced above the central electrode of the spark plug and at its outer end a terminal for connection with a high tension ignition cable. The gap formed between the outer end of the central electrode and the inner end of the short electrode carried by the hood, provides an air space across which the high tension current must pass in the operation of the apparatus. The condition and functioning of the spark 75 plug as an igniter may be ascertained by observance of the nature of the spark passing between this gap. Openings provided in the side-walls of the hood are protected by a transparent window of glass, isinglass or 80 similar material.

Referring more in detail to the specific embodiment of the invention which I have chosen to illustrate for the purpose of making a full and complete disclosure of the invention, the numeral 10 indicates the outer metallic shell of the spark plug threaded at its lower end 11 for screw threaded engagement with the cylinder of a gas engine. The upper end of the shell is of hexagonal 95 shape as at 12 to receive a wrench. A central insulating core 13 of porcelain, or any other suitable insulating material, is provided near its inner end with an annular flange 14, beyond which the diameter of the core is considerably reduced as at 15 to lie within, and may be spaced from, the lower end of the shell 10. The flange portion 14 of the core lies within the enlarged upper end portion of the shell 10 and at its inner 100 end co-operates with the shoulder 16 formed within the shell, its upper edge co-operating with the inner end of a nut 17 which is in screw threaded engagement with the inner 105 upper end of the shell 10. Packing rings 18 110

and 19 engage the upper and lower edges of the shoulder 14 to allow for uneven expansion of the parts and provide a gas tight seal.

5 A central opening is provided throughout the length of the core to receive the central electrode 20, the inner end of which is enlarged as at 21 where it lies within the enlarged opening 22 in the inner end of the 10 core. Diverging wings 23 extend radially from the inner end of the central electrode to lie in close proximity to the inner wall of the shell 10 providing air spaces across which passes the spark for igniting the compressed gas vapor within the engine cylinder. The upper end of the central electrode 20 extends a short distance above the end of the core and is threaded as at 24 to receive a nut 25 for clamping the central electrode 20 in its position within the core.

The spark gap proper comprises a dome shaped hood or shell, 26, the lower portion of which is flanged outwardly as at 27 to extend over an annular projection or head 25 28 formed on the outer end portion of the core. The interior of the flange 27 is threaded for engagement with the threaded nut 29 which is divided into two parts on a diametric plane each part having an inwardly 30 extending bead 30 for engagement with the under side of the annular projection 28. Annular rings or washers 31 are positioned at the upper and lower sides of the annular projection 28 to prevent damage to the core 35 when the two, interengaging parts are screwed together with sufficient pressure to hold the hood in position.

An electrode 32 extends through an opening in the top of the hood 26 and at its 40 inner end is provided with a button-shaped, annular enlargement 33 of a shape somewhat similar to the upper end of the dome 26, but of a less diameter at its inner edge 26, but of a less diameter at its inner edge so that its inner edge will be spaced somewhat 45 away from the side wall of the dome to receive and position the upper edge of a cylinder of transparent material 34 which may be of glass, isinglass or similar substances. The side wall of the dome is provided with apertures as at 35 so as to permit observation of the spark gap through the transparent material 34. A centrally disposed projection 36 extends from the center of the electrode 32 into close prox-

imity with the upper end 24 of the central 55 electrode, but is spaced apart a slight distance to permit an air gap across which the high tension current must pass. The portion of the electrode 32 which passes through the top of the hood is flattened as at 37 for co-operation with the similarly shaped opening in the hood preventing rotation of the electrode with respect to the hood. The upper portion of the electrode 32 is screw-threaded to receive the clamping nut 38 60 65 which locks the same in position within the hood and a terminal screw 39 is threaded on its upper end for engagement with the terminal clip of a high tension ignition cable. 70

Whereas I have illustrated and described but a single embodiment of my invention, it will be apparent to those skilled in the art that many changes and modifications may be made therein without departing 75 from the spirit of the invention or the scope of the appended claims.

Having described my invention, what I claim is:—

1. A spark plug comprising a shell, a core 80 of insulating material having an annular projection formed on its outer end portion, a central electrode extending through the core, a spark-gap-inclosing-hood positioned over the end of the core, its inner end portion being flanged to overlie the annular projection on the core, and having threads formed thereon, and a nut formed of a plurality of radially separable parts for co-operation with the threads on the hood to 85 clamp the same on the annular projection. 90

2. A spark plug comprising a shell; a core of insulating material having an annular projection formed on its outer end portion to provide an outer and inner shoulder; 95 a spark-gap-inclosing-hood, positioned over the end of the core, having an inner threaded part encompassing said projection, and having an internal shoulder overlying said outer shoulder; a nut formed of a plurality 100 of radially separable parts for co-operation with said threads in the hood and having inner shoulders underlying said inner shoulder on the core, to secure the hood to the core. 105

In testimony whereof I hereunto set my hand.

JOSEPH RENÉ AYOTTE.
